UNITED STATES PATENT OFFICE.

ANTHONY H. COLLINS, OF BRONXVILLE, NEW YORK, ASSIGNOR TO CHICAGO PNEUMATIC TOOL COMPANY, OF NEW YORK, N. Y., A CORPORATION OF NEW JERSEY.

REFRIGERATING APPARATUS.

Application filed February 16, 1927. Serial No. 168,513.

This invention relates to means for transforming heat with particular relation to refrigerating systems and apparatus. While having application to refrigerating apparatus generally, it particularly concerns mechanically operated refrigerating outfits intended for household use wherein the mechanism of the outfit is placed closely adjacent the compartment or chamber from which heat 5 is to be extracted, as in the lower compartment of a refrigerator cabinet.

It has been proposed to use as a working substance in refrigerating systems of the evaporator-compressor-condenser type a solution of a volatile liquid and a lubricant and to separate out at one point in the cycle the lubricant in a highly concentrated form to be used for lubricating and sealing the working parts. The separation of the lubricant 10 component of the working substance is effected by fractional distillation, usually at the high heat of compression. The pump or compressor accordingly operates at a temperature considerably above room temperature 15 and when placed beneath the refrigerating compartment there is a considerable leakage of heat into the latter with the result that the apparatus tends to operate more frequently and for longer intervals.

One object of the invention is to provide 20 an improved self-contained refrigerating outfit. Another object is to prevent leakage of heat from an apparatus compartment into a refrigerating compartment immediately adjacent thereto or directly thereover. Another object is to utilize the objectionable heat to remove heat from adjacent the refrigerating compartment. Another object is to utilize the objectionable heat for an additional useful purpose. Other objects will be apparent from the detailed description which follows:

The invention consists broadly in providing 25 an atmospheric barrier between the source of heat and the refrigerating compartment. By preference the barrier is a moving column or layer of cool air which removes the heat. The objectionable heat is utilized to induce and maintain the moving barrier and may be caused to serve the additional useful purpose 30 of removing heat from the condenser. The moving column of air may be arranged to serve as ejector means for a chamber in which the condenser is disposed. The chamber for

the condenser may be provided between the apparatus compartment and the refrigerating compartment. The invention further contemplates utilizing insulating material additional to that ordinarily used for the refrigerating compartment and in a manner 40 adapted to increase the velocity of movement of the air stream or streams resulting from the utilization of the undesirable heat.

In order to illustrate the invention concrete embodiments thereof are shown in the accompanying drawings, in which:

Fig. 1 is a vertical sectional view through a self-contained refrigerating cabinet substantially on the line 1—1 of Fig. 2;

Fig. 2 is a rear end elevational view of 70 the cabinet shown in Fig. 1;

Fig. 3 is a fragmentary vertical sectional view of the lower portion of a refrigerating cabinet showing a modified arrangement;

Figs. 4 and 5 are vertical sectional views, 75 partly cut away, showing still further modified forms of the invention.

In the accompanying drawings various modifications of the inventive idea are illustrated. In each instance a self-contained mechanically operated refrigerating outfit is disclosed in which the apparatus is of the condenser-compressor-evaporator type utilizing a lubricating refrigerant in a closed cycle system. The refrigerant preferably comprises a volatile liquid having lubricant in solution in accordance with the disclosure of the copending application of Ransom W. Davenport, Ser. #60,311, filed October 3, 1925—working substances for refrigerating 80 machines, and the lubricant is arranged to be separated out by fractional distillation at the high temperature of compression. The various parts of the refrigerating apparatus may be of any suitable or desired type. 85

Referring now to the embodiment shown in Figs. 1 and 2, the refrigerating outfit therein shown is intended for household use and comprises a cabinet 6 having a chamber 7 with walls insulated against heat and from which heat is intended to be extracted. Adjacent said chamber and preferably therebeneath is a compartment 8 arranged to contain at least a part of the refrigerating apparatus. The apparatus disposed in compartment 8 comprises a pump or compressor 9 and a prime mover such as electric motor 10 arranged to operate the pump, the pump and 95 100 105

motor being combined into a hermetically sealed motor pump unit 9, 10. An evaporator 11 is disposed in chamber 7 and a natural draft air cooled condenser 12 is secured at 5 the back of the cabinet as indicated in Fig. 2. A connection 13 including a feeding device or so-called "expansion valve" 14 extends from condenser 12 to the bottom of the evaporator 11. Pump 9 withdraws vaporized refrigerant from the top of evaporator 11 by 10 a pipe 15 and discharges the same at higher temperature and pressure through pipe 16 into the top of the condenser 12.

Since the separating out of the lubricant 15 component of the refrigerant solution takes place in pump 9 at the high temperature of compression, considerable heat is given off by motor pump unit 9, 10 and it is desirable to protect refrigerating chamber 7 from this 20 undesirable heat. To this end a partition 17 is provided beneath chamber 7 and in spaced relation thereto so as to provide an air chamber 18. In order to effect movement of the air in chamber 18 so as to carry away 25 the heat which leaks through partition 17 from compartment 8, a flue 19 is provided and connected to one end of air chamber 18. The flue is preferably upon the exterior of cabinet 6 and may be at the back of the same as 30 shown in Fig. 2. As a further protection to refrigerating chamber 7, heat insulating material 20, additional to that normally used for said chamber, may be provided, if desired, to form the upper wall of air chamber 18. 35 By reason of the relatively small size of the motor pump unit 9, 10, compartment 8 containing the latter need not occupy all the space beneath refrigerating chamber 7 but by preference is disposed at one side thereof 40 as indicated in Fig. 2 so that the heat from compartment 8 which is carried away by the moving barrier of air produced in chamber 18 and flue 19 may not interfere with the cooling of condenser 12. A narrow partition 21 45 separates the part of the rear wall of cabinet 6 which is utilized for condenser 12 from the part which provides space for flue 19. Compartment 8 is provided with one or more openings 8^a beneath pump 9 and with louvres 50 8^b at the ends to permit a portion of the heat in the compartment to escape.

The modification of the invention disclosed in Fig. 3 is in all respects similar to that of Figs. 1 and 2 except that the air chamber 18 55 is given an upward inclination to facilitate the movement of air therethrough and up flue 19^a which connects with the highest part of the air chamber 18^a. The inclination of air chamber 18^a is effected by placing partition 17^a at a slant as shown and by tapering the additional layer 20^a of insulating material.

In Figs. 4 and 5 the undesirable heat which 60 is generated in the apparatus compartment of the cabinet is utilized to effect the removal

of heat from the condenser and for this purpose the air chamber interposed between the apparatus compartment and the refrigerating chamber to protect the latter from the heat of the compartment may have the condenser disposed therein. The arrangement is preferably such that the heat from the apparatus compartment produces an ejector effect in the air chamber so that a current of air moves through the latter with sufficient 75 velocity and volume to carry away the leakage of heat from the lower compartment and to effectively cool the condenser.

In Fig. 4 the top of the apparatus compartment 8^c is formed by sharply inclining partition 17^b which may be relatively thick and of heat insulating material. The additional layer of insulating material 20^b is also tapered at an angle corresponding to the inclination of partition 17^b so that the air chamber 18^b formed therebetween has a decided upward inclination. The condenser 12^a of the refrigerating system is disposed in chamber 18^b as indicated. The wall 8^d of compartment 8^a at the high end thereof is closed and merges into the outer wall of the flue 19^b which in the present instance is shown at the end of cabinet 6^a so as to give maximum length to air chamber 18^b. It is thus apparent that the higher part of apparatus chamber 8^c opens into flue 19^b with the result that there is a natural upward movement of air from this compartment into flue 19^b. Partition 17^b has an upward and outwardly turned end 17^c which cooperates with flue 19^b to produce an ejector effect with the result that the upward draft of heated air from compartment 8^c induces an active movement of cooled air through air chamber 18^b and over and around condenser 12^a disposed therein.

In Fig. 5 a cabinet 6^b provides a plurality of vertically spaced air chambers which are interposed between the apparatus compartment 8^d and refrigerating chamber 7. In the form shown two such air chambers 23 and 24 are provided formed by spaced partitions 25 and 26. Partition 25 which forms the closed top of compartment 8^d may be of thin sheet material such as metal and may be continued beyond the cabinet to form the exterior wall of flue 27. Partition 26 is preferably relatively thick and of heat insulating material. A wedge-shape layer 28 of additional insulating material may be secured beneath the refrigerating chamber 7, the lower side of said material having an inclination conforming to that of partitions 25 and 26 which are in substantial parallelism with each other. Condenser 12^b of the refrigerating apparatus is disposed in upper air chamber 24. Partition 26 has an angularly disposed end portion 26^a arranged to project into flue 27 to cooperate with the latter in causing the rising current of air in chamber 23 to have an ejector effect upon air chamber

24 so as to produce effective removal of heat from condenser 12^b.

5 While various preferred forms of the inventive idea herein disclosed have been shown and described, it is to be understood that the invention is not limited to the specific details thereof, but covers all changes, modifications, and adaptations within the scope of the appended claims.

10 I claim as my invention:

1. A self-contained refrigerating outfit providing a chamber from which heat is to be extracted, a compartment adjacent said chamber for at least part of the refrigerating apparatus, a wall of heat insulating material between said chamber and said compartment, and means providing an air chamber between said refrigerating chamber and said compartment adjacent said wall.

15 2. A self-contained refrigerating outfit providing a chamber from which heat is to be extracted, an insulating wall for said chamber, a compartment beneath said chamber for at least part of the refrigerating apparatus, and means providing an air chamber between said refrigerating chamber and said compartment beneath said wall.

20 3. A self-contained refrigerating outfit providing a chamber from which heat is to be extracted, a wall of heat insulating material for said chamber, a compartment adjacent said chamber for at least part of the refrigerating apparatus, and means providing a barrier of moving fluid between said refrigerating chamber and said compartment along said wall.

25 4. A self-contained refrigerating outfit providing a chamber from which heat is to be extracted, an insulating wall for said chamber, a compartment beneath said chamber for at least part of the refrigerating apparatus, and means providing a barrier of moving fluid between said refrigerating chamber and said compartment beneath said wall.

30 5. A self-contained refrigerating outfit comprising a cabinet having a refrigerating chamber with walls of insulated material, a compartment beneath said refrigerating chamber, means for extracting heat from said chamber, at least a part of said means being disposed in said compartment, and means providing an upwardly directed air chamber between said chamber and said compartment.

35 6. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an air chamber between said chamber and said compartment, and heat insulating material arranged to give said air chamber an upward inclination.

40 7. A self-contained refrigerating outfit

comprising a cabinet having a refrigerating chamber with walls of insulating material, a compartment beneath said refrigerating chamber, means for extracting heat from said chamber, at least a part of said means being disposed in said compartment, means providing an air chamber between said chamber and said compartment, heat insulating material arranged to give said air chamber an upward inclination, and means forming a flue connected to said air chamber for inducing movement of air therethrough.

8. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an upwardly directed air chamber between said chamber and said compartment, and a flue connected to said air chamber to induce movement of air therethrough.

9. A self-contained refrigerating outfit comprising a cabinet having a refrigerating chamber with walls of insulating material, a compartment beneath said refrigerating chamber, means for extracting heat from said chamber, at least a part of said means being disposed in said compartment, and means providing an upwardly directed air chamber between said chamber and said compartment, and a flue upon the exterior of said cabinet and connected to said air chamber to induce movement of air therethrough.

10. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an air chamber between said chamber and said compartment, heat insulating material arranged to give said air chamber an upward inclination, and a flue connected to the highest part of said air chamber.

11. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an air chamber between said chamber and said compartment, heat insulating material arranged to give said air chamber an upward inclination, a flue connected to the highest part of said air chamber, and means utilizing heat in said compartment for inducing movement of air through said air chamber.

12. A self-contained refrigerating outfit comprising a cabinet having a refrigerating chamber with walls of insulating material, a compartment beneath said refrigerating

- chamber, means for extracting heat from said chamber, at least a part of said means being disposed in said compartment, means providing an upwardly directed air chamber between said chamber and said compartment, and ejector means utilizing undesirable heat in said compartment for inducing movement of air through said air chamber.
13. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an upwardly directed air chamber between said chamber and said compartment, a flue connected to said chamber, and means cooperating with said flue for inducing movement of air through said air chamber.
14. A self-contained refrigerating outfit comprising a cabinet having a refrigerating chamber with walls of insulating material, a compartment beneath said refrigerating chamber, means for extracting heat from said chamber, at least a part of said means being disposed in said compartment, means providing an upwardly directed air chamber between said chamber and said compartment, a flue connected to said air chamber, and means extending into said flue and cooperating therewith for utilizing heat from said compartment for inducing movement of air through said air chamber.
15. A self-contained refrigerating outfit providing a chamber from which heat is to be extracted, a compartment adjacent said chamber for at least part of the refrigerating apparatus, means providing an air chamber between said refrigerating chamber and said compartment, a condenser in said air chamber, and means inducing movement of air through said air chamber and over said condenser.
16. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, and means utilizing the undesirable heat given off by said motor-pump unit for removing heat from said condenser.
17. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, and means protecting said chamber from the heat given off by said motor-pump unit and utilizing said heat for removing heat from said condenser.
18. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, said cabinet providing an air chamber between said compartment and said refrigerating chamber, said condenser being disposed in said air chamber.
19. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, and means between said refrigerating chamber and said compartment forming an upwardly inclined air chamber, said condenser being disposed in said air chamber.
20. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, said cabinet providing an air chamber between said compartment and said refrigerating chamber, and a flue connected to said air chamber, said condenser being disposed in said air chamber.
21. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, said cabinet providing an air chamber between said compartment and said refrigerating chamber, said condenser being disposed in said air chamber, and means utilizing the heat in said compartment for inducing movement of air through said air chamber and over said condenser.
22. A self-contained refrigerating outfit comprising a cabinet having a refrigerating chamber, a compartment beneath said chamber, refrigerating apparatus forming a closed cycle system including an evaporator in said chamber, a motor-pump unit in said compartment, and a condenser, means between said refrigerating chamber and said compartment forming an upwardly inclined air chamber, said condenser being disposed in said air chamber, a flue connected to the upper part of said chamber, and means cooperating with said flue for utilizing heat in said compartment to induce movement of air through said air chamber and over said condenser.
23. A self-contained refrigerating outfit comprising a cabinet having a refrigerating chamber, a compartment beneath said chamber, refrigerating apparatus forming a closed cycle system including an evaporator in said chamber, a motor pump unit in said compartment.

ment, and a condenser, said cabinet providing an air chamber between said compartment and said refrigerating chamber, and means including an ejector utilizing heat given off by said motor-pump unit for inducing movement of air through said chamber.

24. A refrigerator cabinet having a chamber with walls insulated against heat and from which heat is to be extracted, a compartment for at least a part of the refrigerating apparatus disposed beneath said chamber, and a plurality of vertically spaced air chambers between said insulated chamber and said compartment.

25. A refrigerator cabinet having a chamber with walls insulated against heat and from which heat is to be extracted, a compartment for at least a part of the refrigerating apparatus disposed beneath said chamber, a plurality of vertically spaced air chambers between said insulated chamber and said compartment, and means giving said air chambers an upward inclination to induce a current of air therethrough.

26. A refrigerator cabinet having a chamber with walls insulated against heat and from which heat is to be extracted, a compartment for at least a part of the refrigerating apparatus disposed beneath said chamber, vertically spaced partitions between said insulated chamber and said compartment providing upwardly inclined air chambers, and a flue connected to the upper ends of both said air chambers.

27. A refrigerator cabinet having a chamber with walls insulated against heat and from which heat is to be extracted, a compartment for at least a part of the refrigerating apparatus disposed beneath said chamber, and a plurality of vertically spaced air chambers between said insulated chamber and said compartment, and a condenser in one of the said chambers.

28. A refrigerator cabinet having a chamber with walls insulated against heat from which heat is to be extracted, a compartment for at least a part of the refrigerating apparatus disposed beneath said chamber and

said compartment, and means giving said air chambers an upward inclination to induce movement of air therethrough, and a condenser in the highest of said air chambers.

29. A refrigerator cabinet having a chamber with walls insulated against heat and from which heat is to be extracted, a compartment for at least a part of the refrigerating apparatus disposed beneath said chamber, vertically spaced partitions between said insulated chamber and said compartment providing upwardly inclined air chambers, a flue connected to the upper ends of both said air chambers, and means cooperating with said flue whereby one of said air chambers serves as an ejector for the other.

30. A refrigerator cabinet having a chamber with walls insulated against heat and from which heat is to be extracted, a compartment for at least a part of the refrigerating apparatus disposed beneath said chamber, vertically spaced partitions between said insulated chamber and said compartment providing upwardly inclined air chambers, a flue connected to the upper ends of both said air chambers, and a condenser in the higher of said air chambers.

31. A self-contained refrigerator outfit comprising a cabinet having a refrigerating chamber, a compartment beneath said chamber, refrigerating apparatus forming a closed cycle system including an evaporator in said chamber, a motor-pump unit in said compartment, and a condenser, means providing vertically spaced upwardly inclined air chambers between said refrigerating chamber and said compartment, said condenser being disposed in the higher of said air chambers, a flue connected to the upper ends of both said air chambers, and means cooperating with said flue whereby heat from said motor-pump unit carried away by the current of air in said lower air chamber serves to induce movement of air through said upper chamber.

Signed by me at New York, New York, this 11th day of February, 1927.

ANTHONY H. COLLINS.
